AUTOMATIC CUT-OFF FOR PUMPS.

APPLICATION FILED MAR. 27, 1905.

2 SHEETS—SHEET 2.

UNITED STATES PATENT OFFICE.

JEREMIAH MURPHY, OF LEADVILLE, COLORADO, ASSIGNOR TO CHARLES T. CARNAHAN, OF LEADVILLE, COLORADO.

AUTOMATIC CUT-OFF FOR PUMPS.

No. 800,003.

Specification of Letters Patent.

Patented Sept. 19, 1905.

Application filed March 27, 1905. Serial No. 252,335.

To all whom it may concern:

Be it known that I, JEREMIAH MURPHY, a citizen of the United States, residing at Leadville, in the county of Lake and State of Colorado, have invented new and useful Improvements in Automatic Cut-Offs for Pumps, of which the following is a specification.

This invention relates to automatic cut-offs particularly adapted for use in automatically cutting off motive fluid to a pump, although the same is adapted to any use for which it is found applicable, and the object thereof is to provide an automatic cut-off which will be thrown into operation if the pump should jar, thereby cutting off the supply of motive fluid, causing automatically the discontinuing of the operation of the pump, thereby preventing the pump becoming injured.

The invention further aims to provide an automatic cut-off for pumps or for other purposes for which it is applicable which shall be simple in its construction, strong, durable, automatic and instantaneous in its operation, efficient in its use, and comparatively inexpensive to set up.

With the foregoing and other objects in view the invention consists in the novel construction, combination, and arrangement of parts hereinafter more specifically described, illustrated in the accompanying drawings, which form a part of this specification, and particularly pointed out in the claims hereunto appended.

In describing the invention in detail reference is had to the accompanying drawings, wherein like reference characters denote corresponding parts throughout the several views, and in which—

Figure 1 is a side elevation of a double-acting pump, showing the automatic cut-off in accordance with this invention arranged in operative relation with respect to the pump. Fig. 2 is an end elevation thereof. Figs. 3 and 4 are respectively a side and end elevation of the support for the gravity-operating trip-bar. Fig. 5 is an end view showing the arrangement of the gravity-operating trip-bar with respect to its support, and Fig. 6 is a like view showing the trip-bar in its operative position.

Referring to the drawings by reference characters, 1 denotes the double-acting pump, and 2 the motive-fluid-supply pipe, which is provided with an automatically-operating

cut-off in the form of a double valve, as at 3, 55 the stem 4 of said double valve projecting below the pipe 2. A pair of seats 5 is provided for the valves 3.

When the device is used in connection with a double-acting pump, a pair of supports is 60 provided. If used in connection with a single-acting pump, but one support is necessary.

The reference character 6 denotes the supports which are secured to the pump in any suitable manner and are substantially of inverted-L shape. The upper face of the horizontal member of each of the supports is provided with a pair of indentations, as at 7. Each of the supports 6 is also provided with guides 8, retained in position by the set-screws 9. Extending through the guides 8 are the gravity-operating trip-bars 10, carrying on their lower ends the weights 11 and having a curved upper portion 12, which terminates in a horizontally-extending portion 13, 75 adapted to project over the horizontally-extending portion of the supports, and the said horizontally-extending portions 13 are provided with a pair of barbs 14, which are adapted to find a seat in the indentations 7. 80 The arrangement of the bars 10 with respect to the supports 6 is such that on the least jar of the pump the rods will be caused to move off the supports 6, and consequently, owing to the action of the weights 11, the bars 10 85 will fall by gravity, thereby throwing into operation automatically the cut-off.

To each of the bars 10 is connected, as at 14, a pair of pulling-arms 15, suitably secured at their upper ends, as at 16, to the counter-weighted rock-arm 17, which is mounted in the bearing 18 and carries near one end the crank-arm 19, which is pivoted, as at 20, to a pulling-arm 21, pivoted, as at 22, to a bolt 23, extending through a latch 24, depending from 95 the pipe 2. Depending from the pipe 2 is a hanger 25, to which is pivoted one end of a trip-lever 26, as at 27. Said lever 26 is also connected, as at 28, to the lower end of a stem 4 and has its free end bent at an 100 angle, as at 29, which is adapted to rest upon the bolt 23 when the mechanism which constitutes the cut-off is set up in inoperative position.

The manner in which the cut-off operates is 105 as follows: In case anything should happen to the pump or motive-fluid pipe—such as water in the steam-cylinders, pistons overreaching

gaskets, blowing on pump or water column, dropping a valve, getting air in the water-cylinder, or anything else that endangers the pump being broken or will cause the pump 5 to jar or jump during the stroke—this jar or jump causes the barbs 14 to be thrown out of the indentations 7 and which will cause the bars 10 to fall by gravity, thereby carrying the elements 15 therewith, rocking the arm 10 17, moving the crank 18 in one direction, which in turn carries the arm 21 therewith, the latter moving the bolt 23 from beneath the right-angular portion 29 of the lever 26, causing the lever 26 to fall, which in turn 15 carries the stem and causes the valves 3 to become seated, thereby cutting off the supply of motive fluid and discontinuing the operation of the pump.

Although, preferably, the gravity-operating trip-bars 10 are displaced off the support 20 through the means of a jar, yet the cut-off can be so adjusted that when the pump exceeds the maximum speed limit set therefor the gravity-operating trip-bars 10 will be displaced, so as to automatically cut off the supply of motive fluid, the displacing of the trip-bars causing the operation of the mechanism in a manner as hereinbefore referred to.

Having thus fully described my invention, 30 what I claim as new, and desire to secure by Letters Patent, is—

1. An automatic cut-off for motive fluid, comprising means operated by a jar of a pump or engine for throwing the cut-off into operation, thereby closing the supply of motive 35 fluid.

2. An automatic cut-off for motive fluids, comprising a vertically-movable and gravity-operable mechanism operated by a jar of a 40 pump or engine for throwing the cut-off into operation, thereby closing the supply of motive fluid.

3. An automatic cut-off for motive fluid, comprising the combination with a motive-fluid-supply pipe, of a valve for opening and closing said pipe, and mechanism operated by a jar of a pump or engine and connected with said valve for automatically operating it, thereby closing the said pipe.

4. An automatic cut-off for motive fluid, comprising the combination of a supply-pipe and a valve for opening and closing said pipe, of mechanism connected with said valve for closing it, and a gravity-operable trip-bar 55 operated by a jar of a pump or engine and connected with said mechanism for operating it, thereby closing said valve.

5. An automatic cut-off for motive fluid, comprising the combination of a supply-pipe and a valve for opening and closing said pipe, of a lever connected with said valve for closing it, a latch mechanism for retaining the lever in an elevated position, thereby retaining the valve open, and mechanism operated 60 by a jar of a pump or engine and connected

with said latch mechanism and adapted when operated to operate the latch mechanism, thereby permitting the lever to fall, thereby closing the valve.

6. An automatic cut-off comprising a support provided with a pair of indentations, a gravity-operating bar having a pair of barbs adapted to be seated in said indentations and suspended by said support, said bar thrown off the support by a jar, a motive-fluid-supply pipe, a valve for opening and closing said pipe, a lever for retaining said valve in its open position, a latch for supporting said lever, thereby retaining the valve open, and mechanism connected with the bar and with the latch and adapted when the bar is operated to shift the said latch, thereby permitting the lever to fall and the valve to close. 75

7. The combination with a pump and a motive-fluid-supply pipe therefor, of a valve for 80 opening and closing said pipe, and means connected with the valve and operated when the pump jars for automatically closing said valve.

8. An automatic cut-off comprising a support provided with a pair of indentations, an automatically-displaceable gravity-operating bar having a pair of barbs adapted to be seated in said indentations and suspended by said support, a motive-fluid-supply pipe, a valve for opening and closing said pipe, a lever for 85 retaining said valve in its open position, a latch for supporting said lever, thereby retaining the valve open, and mechanism connected with the bar and with the latch and adapted when the bar is displaced to shift the latch, thereby permitting the lever to fall and the valve to close. 90

9. An automatic cut-off comprising a support, a vertically-movable and automatically-displaceable gravity-operating bar suspended 105 by said support, a motive-fluid-supply pipe, a valve for operating and closing said pipe, a lever for retaining said valve in its open position, a latch for supporting said lever, thereby retaining the valve open, and mechanism connected with the bar and with the latch and adapted when the bar is displaced to shift the latch, thereby permitting the lever to fall and the valve to close. 110

10. An automatic cut-off for motive fluids, comprising the combination of a supply-pipe, and a valve for opening and closing said pipe, of a lever connected with said valve for closing it, a mechanism for retaining the lever in an elevated position, thereby retaining the valve open, and a vertically-movable and automatically-displaceable gravity-operating bar connected with said mechanism and adapted when displaced to operate the said mechanism, thereby permitting the lever to fall and the valve to close. 115

11. An automatic cut-off for motive fluids, comprising the combination of a supply-pipe and a valve for opening and closing said pipe, of a mechanism connected with said valve for 120

closing it, and a vertically-movable automatically-displaceable gravity-operable trip-bar connected with said mechanism and adapted when displaced to operate the mechanism, 5 thereby closing said valve.

12. The combination with a pump or engine and a motive-fluid-supply pipe therefor, of a valve for opening and closing said pipe, of a support, a gravity-operable bar having a barb 10 seated upon said support, thereby suspending the bar, and means connected with the bar

and with the valve and adapted when the bar is displaced off of said support to close the valve.

In testimony whereof I have hereunto set 15 my hand in presence of two subscribing witnesses.

JEREMIAH MURPHY.
